(57) **CLAIM**

The ornamental design for a shaver handle, as shown and described.

DESCRIPTION

FIG. 1 is a perspective view of a shaver handle according to the present invention;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top end view thereof;

FIG. 7 is a bottom end view thereof;

FIG. 8 is a perspective view of a shaver handle according to another embodiment of the present invention;

FIG. 9 is a rear elevational view thereof;

FIG. 10 is a front elevational view thereof;

FIG. 11 is a right side elevational view thereof;

FIG. 12 is a left side elevational view thereof;

FIG. 13 is a top end view thereof; and,

FIG. 14 is a bottom end view thereof.

The broken lines in the figures are for illustrative purposes only and form no part of the claimed design. Surfaces of the shaver handle being disclaimed are distinguished from the claimed portions by the lack of surface shadings.
